Primary Examiner — Rebekah A Caruso*Assistant Examiner* — Cole Sanders Holman(57) **CLAIM**

The ornamental design for a cat wand toy, as shown and described.

DESCRIPTION

FIG. 1 is a front and top perspective view of a cat wand toy, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion indicated with numeric 9 in FIG. 1; and,

FIG. 10 is another perspective view thereof, shown in an alternative position.

The dashed lines in the figures illustrate portions of the cat wand toy that form no part of the claimed design. The dash dot dash lines in FIGS. 1 and 9 are for the purpose of depicting the boundary lines of the enlarged view and form' no part of the claimed design.

1 Claim, 10 Drawing Sheets(56)
